UNITED STATES PATENT OFFICE.

STANLEY WASS, OF ST. LOUIS, MISSOURI.

DESIGN FOR A SHOE.

45,080.

Specification for Design.

Patented Dec. 23, 1913.

Application filed August 30, 1913. Serial No. 787,550. Term of patent 3½ years.

To all whom it may concern:

Be it known that I, STANLEY WASS, a citizen of the United States, residing at St. Louis, State of Missouri, have invented a new, original, and ornamental Design for Shoes, of which the following is a specification, reference being had to the accompanying drawing, forming part thereof.

The figure is a perspective of a shoe, showing my new design.

I claim:

The ornamental design for a shoe, as shown.

STANLEY WASS.

Witnesses:

JNO. S. DAVIS,
T. H. GODDARD.
